ATTORNEY.

UNITED STATES PATENT OFFICE.

ALBERT U. GRUMMANN, OF INDIANAPOLIS, INDIANA, ASSIGNOR OF ONE-HALF TO JOHN WAGNER, OF SAME PLACE.

BARREL-SKID.

SPECIFICATION forming part of Letters Patent No. 366,626, dated July 12, 1887.

Application filed April 14, 1887. Serial No. 234,863. (No model.)

To all whom it may concern:

Be it known that I, ALBERT U. GRUMMANN, of the city of Indianapolis, county of Marion, and State of Indiana, have invented certain new and useful Improvements in Barrel-Skids, 5 of which the following is a specification.

My present invention consists in certain improvements upon that shown and described in Letters Patent No. 311,655, dated February 10, 1885, whereby a less expensive and in some respects more convenient device for the purpose is produced, as will be hereinafter more particularly described.

Referring to the accompanying drawings, 15 which are made a part hereof, and on which similar letters of reference indicate similar parts, Figure 1 is a perspective view of my improved skid in position for use; and Fig. 2 is a detail sectional view through a portion 20 thereof, showing the parts of the stand more clearly.

In said drawings, the portions marked A represent the frame of the support of my improved skid; B B', the legs to said frame; C, 25 a common skid, which is used for rolling the barrels onto said frame; and D, a jointed skid which is used for rolling them from said frame onto the tier or pile of barrels already in place. The frame A is preferably a casting, 30 and consists of two circles connected together by arms. The outer circle is adapted to receive the ends of the skids, and the inner circle (which should be higher than the outer circle) serves as a track on which to whirl the 35 barrels when, as in many cases, they are rolled onto it from one direction and are to be rolled off in another. The frame A being circular permits any variation in direction desired, as the skids will rest equally well upon 40 any portion of the outer circle.

The legs consist of the two parts B B', connected together by clips or clasps, one of which, b, is bolted firmly to the lower end of the part B, and the other, b', to the upper 45 end of the part B'. One or the other, or both, of said parts have also numerous holes, as shown, and one or both of said clips are provided with a corresponding hole or holes, through which a pin, b², may be inserted; and 50 thus by simply removing said pin the legs can be adjusted to any length desired and

there held by said pins when reinserted, as will be plainly understood by an examination of the drawings. Thus the device is adapted for use in piling two or more tiers of barrels 55 as well as a single tier.

The skid C is a skid of the ordinary and well-known construction, and is used to roll barrels from any point desired to the top of the frame A.

The skid D consists of a series of jointed sections which are capable of folding one inside the other, the sections being preferably of a length just equal to the distance from center to center of barrels when laid together in a 55 tier, as shown. Thus the barrels can be rolled along on top of a tier, one by one, and the section which is at the time the outer section of the skid folded up after each barrel is placed in position, until finally the entire skid is 60 folded up, thus providing a smooth track on which to roll the barrels to any distance desired. This skid is especially valuable in rolling barrels into a tier between two tiers which have already been piled, where there is 65 little or no room for the workmen to grasp the barrel.

Having thus fully described my said invention, what I claim as new, and desire to secure by Letters Patent, is—

1. The combination, with a skid, of a circular frame formed with a raised central portion and an outer flange, said outer flange being adapted to furnish a support for the raised end of said skid, substantially as set forth.

2. A support for skids, consisting of a circular frame the central portion of which is higher than the outer portion, substantially as set forth.

3. In a barrel-skid, a support for the raised 90 end, the frame of which consists of two circles, one of which serves to receive the ends of the skids, and the other of which serves as a track on which to turn or whirl the barrel, substantially as set forth.

4. The combination of an ordinary skid, a stand having a circular top for supporting the raised end of the skid, and a second skid or track running from said stand out over the tops of the barrels, substantially as set forth.

5. The combination of an ordinary skid, a supporting-stand for its raised end, and a sec-

ond skid running out over the tops of the barrels, consisting of a series of jointed sections adapted to be folded together, each outer section within the next inner section, substantially as set forth.

6. The combination of the circular frame A, mounted on adjustable legs, its central portion being formed higher than its outer portion, the common skid C, and the jointed skid D,

the sections of which fold within each other, substantially as set forth.

In witness whereof I have hereunto set my hand and seal, at Indianapolis, Indiana, this 9th day of April, A. D. 1887.

ALBERT U. GRUMMANN. [L. S.]

In presence of—

C. BRADFORD,

PAUL H. GRUMMANN.
